C. Müller

UNITED STATES PATENT OFFICE.

CAROLINE MÜLLER, OF NEW ORLEANS, LOUISIANA.

LIFTER AND CARRIER FOR BATH-TUBS, &c.

SPECIFICATION forming part of Letters Patent No. 693,300, dated February 11, 1902.

Application filed June 20, 1901. Serial No. 65,348. (No model.)

To all whom it may concern:

Be it known that I, CAROLINE MÜLLER, a citizen of the United States, residing at New Orleans, in the parish of Orleans and State of Louisiana, have invented certain new and useful Improvements in Lifters and Carriers for Bath-Tubs, &c.; and I do hereby declare the following to be a full, clear, and exact description of the invention, such as will enable others skilled in the art to which it appertains to make and use the same.

My invention relates to improvements in lifters and carriers for bath-tubs, &c., and is more especially adapted for use in hospitals and the like for providing a safe means for bathing patients in a more or less helpless condition.

In order to more fully explain my said invention, reference will be had to the accompanying drawings, in which—

Figure 1 represents a plan view of a portion of my said invention. Fig. 2 is a perspective view showing the complete apparatus applied to a tub, and Fig. 3 is an enlarged detail view of one form of motor operating mechanism.

In the accompanying drawings my said invention is shown as applied to an ordinary tub. However, it will be obvious that the devices can be changed slightly, so as to accommodate the same to any bathing contrivance.

Referring first to Fig. 2, K K represents a frame having uprights secured to each end of the tub, said frame forming an arch above the tub. B B are pulleys mounted securely in the frame K K. A A are ropes or cords, four in number, one of said ropes being secured to each corner of a swinging table or

platform F, preferably perforated, as shown. Mounted in the top of said frame K K is a cylinder D, having a piston-head a and piston-rod b adapted to reciprocate therein. Connected to the free end of the piston-rod

b is a set of independently-mounted pulleys G, said pulleys being adapted to slide back and forth upon the frame K K. J is a second set of pulleys mounted stationary in the frame K K. H is a feed-pipe connected to a source of fluid-pressure supply communicating with the rear end of said cylinder D, the fluid-pressure from said pipe H forcing said

piston-head a and rod b outwardly, thereby increasing the space between the pulleys G and J. Over these pulleys G and J are adapted to pass the ropes or cords A A, supporting the table or platform F. Thus it will be seen that when the pulleys G and J are separated the table F is raised and when brought together is lowered. C is a cylinder in which is adapted to reciprocate the piston f g, operated by the lever or handle h. This cylinder is connected to a source of fluid-supply E and the fluid-supply pipe H, the check-valves d d intervening, causing the cylinder and its piston to operate as a pump. m is a return-pipe connected to the fluid-supply pipe H, provided with a release-valve e.

The operation of the apparatus is as follows: Assuming that the platform or table F is in the uppermost position, as shown in Fig. 2, the valve e in the return-pipe m is opened, allowing the fluid in the cylinder D to be forced out by the tension upon the cords A A, forcing the pulleys G and J together, due to the weight upon the platform F. This fluid-pressure passes from the cylinder D through the pipe H, valve e, and pipe m and is discharged into the tank or receptacle E. When the platform F has descended the proper distance, the valve e is closed and the platform is raised to its former position by operating the pump C, forcing fluid from the tank E through the pipe H into the cylinder D, thereby forcing the piston-rod b of the cylinder D outwardly, thereby separating the pulleys G and J, thus raising the platform F. This platform or table F is preferably composed of a framework of rods f', interwoven with wire f'', upon which is laid a perforated rubber cover f''. When a cover and platform of this character are used, the draining of water from the same is very rapid, another advantage being that the water is allowed to flow up through the platform while being lowered into the tub.

This apparatus is generally used in hospitals and the like for removing very ill patients from the bed to the bath-tub and back again without subjecting them to any exertion. Therefore the tub or other device upon which the appliance is mounted is generally provided with rollers I I to allow the tub to be drawn up beside the bed or the like.

The swinging platform F is then swung over upon the bed and the patient slid upon it. The platform is then elevated until clear of the bed and then lowered into the tub. The platform is again raised and then swung upon the edge of the bed and the patient removed. This appliance may also be employed for transferring patients from an operating-table to a bed or from one bed to another, as will be obvious.

The valve X, controlling the inlet and outlet of water to the tub, is carried by the tub, to which a hose might be connected for filling the tub, the water being allowed to run directly into a sewer in emptying the tub.

While I have illustrated and described my apparatus as attached to an ordinary tub provided with rollers and adapted to be operated by fluid-pressure, it is obvious that the same may be operated in any suitable manner, such as by electricity and the like. It is also obvious that many changes might be made in my said invention without departing from the spirit thereof and that the details thereof may be altered to suit varying requirements.

Having thus described my said invention, what I claim, and desire to secure by Letters Patent of the United States, is—

1. The combination with a movable tub or receptacle for the invalid, of a frame mounted above said tub or receptacle, pulleys carried by said frame, a platform, ropes or cords running over said pulleys and connected to said platform and means for varying the distance between the pulleys to raise or lower the platform, substantially as described.

2. The combination with a movable tub or receptacle for the invalid, of a frame mounted above said tub or receptacle, pulleys carried by said frame, a platform, ropes or cords running over said pulleys and connected to said platform, a cylinder and piston interposed between said pulleys, and means for supplying fluid-pressure to said cylinder, substantially as described.

3. The combination with a movable tub or receptacle for the invalid, of a frame mounted above said tub or receptacle, pulleys car-

ried by said frame, a platform, ropes or cords running over said pulleys and connected to said platform, a cylinder and piston interposed between said pulleys, and a hand-pump for supplying fluid-pressure to said cylinder, substantially as described.

4. The combination with a tub, mounted on rollers, for the invalid, of a frame mounted above said tub or receptacle, pulleys carried by said frame, a platform composed of a framework of rods of metal covered with a wire fabric and a perforated rubber mat above the same, ropes or cords running over said pulleys and connected to said platform and means for varying the distance between the pulleys to raise or lower the platform, substantially as described.

5. The combination with a tub, mounted on rollers, for the invalid, of a frame mounted above said tub or receptacle, pulleys carried by said frame, a platform composed of a framework of rods of metal covered with a wire fabric and a perforated rubber mat above the same, ropes or cords running over said pulleys and connected to said platform, a cylinder and piston interposed between said pulleys, and means for supplying fluid-pressure to said cylinder, substantially as described.

6. The combination with a tub, mounted on rollers, for the invalid, of a frame mounted above said tub or receptacle, pulleys carried by said frame, a platform composed of a framework of rods of metal covered with a wire fabric and a perforated rubber mat above the same, ropes or cords running over said pulleys and connected to said platform, a cylinder and piston interposed between said pulleys, and a hand-pump for supplying fluid-pressure to said cylinder, substantially as described.

In testimony whereof I affix my signature in presence of two witnesses.

CAROLINE MÜLLER.
